UNITED STATES PATENT OFFICE.

ALBERT C. HOLZAPFEL AND ARTHUR M. HOLZAPFEL, OF NEW YORK, N. Y.

ROTARY BRUSH.

Application filed September 7, 1922. Serial No. 586,739.

To all whom it may concern:

Be it known that we, ALBERT C. HOLZAPFEL and ARTHUR M. HOLZAPFEL, a citizen of the United States and a subject of the King 5 of Great Britain, respectively, residing at New York, in the county of New York and State of New York, have invented certain new and useful Improvements in Rotary Brushes, of which the following is a specification.

This invention relates to rotary brushes, and more particularly to laminated scraping brushes.

An object of the invention is the provision 15 of a brush having flat laminated elements to reduce breakage.

In the present invention, we provide a hub grooved interiorly for the reception of a fastening wire and having a plurality of 20 radial openings through which the plates project. The inner ends of the plates are provided with openings for the passage of the fastening wire. It has heretofore been customary to employ a looped plate with the 25 fastening wire passing through the loop to retain the wire in position. We have found that in such brushes, the breakage generally occurs at the bottom of the loop adjacent the hub, and we, therefore, provide straight 30 plates fastened at their inner ends and laminated on each side.

In cleaning surfaces covered with hard 35 rust, scale and the like, we employ a brush consisting of plates, and centrifugally operated hammers. The hammers are slightly longer than the plates and are pivoted to small spindles attached to the hub. The 40 number of hammers employed may be varied within desired limits, but we have found it advantageous to employ one or more hammers to each circumferential row of 45 scraping elements and have the hammers extending spirally of the brush so that only one or two hammers contact with the surface to be cleaned at the same time.

In the accompanying drawings, we have shown several embodiments of the invention. In this showing:

Figure 1 is a front elevation of one form 50 of brush,

Figure 2 is a transverse sectional view on line 2-2 of Figure 1,

Figure 3 is a similar view on line 3-3 of Figure 1,

Figure 4 is a detail view of one of the 55 laminated scraping elements,

Figure 5 is a similar view of one of the pivoted hammers,

Figure 6 is a front elevation of another 60 form of brush,

Figure 7 is a transverse sectional view thereof, on line 7-7 of Figure 6,

Figure 8 is a detail sectional view on line 8-8 of Figure 6,

Figure 9 is a similar view on line 9-9 of 65 Figure 6,

Figure 10 is an end elevation of one form of hub,

Figure 11 is a plan view thereof,

Figure 12 is a side elevation of another 70 form of hub,

Figure 13 is an interior view of another form of hub,

Figure 14 is an interior view of the hub 75 shown in Figure 12,

Figure 15 is a side elevation of the hub shown in Figure 13, and,

Figure 16 is a detail view of the scraping 80 element showing another manner of retaining the same in position.

Referring to Figures 1 to 5 of the drawings, the reference numeral 1 designates a hub which, as shown, is formed in two sections substantially semi-circular in cross section. The interior of each section is cut 85 out, forming a substantially circular opening through the hub when the sections are assembled. These sections are adapted to be mounted on a driving spindle 2 and retained thereon by suitable fastening element 3. In 90 this form of the invention, the scraping elements are shown arranged in circumferential rows. The inner face of each hub section is provided with a plurality of grooves 4 and radial openings 5 extending through 95 the hub from the exterior, communicating with these grooves. As shown, the outer edges of the openings are rounded (see Figure 2). Each scraping element consists of a central plate 6, and shorter plates 7 and 8, 100 arranged on each side thereof, forming a laminated scraping element. In the use of the brush, the center element 6 touches the surface for cleaning and the shorter elements merely reinforce or strengthen it. 105 The lower ends of each of the plates of the scraping element are provided with openings 9. These openings are adapted to re-

ceive a fastening wire 10, arranged in the groove 4.

For removing hard rust, scale, and the like, a plurality of pivoted hammers 11 are arranged on the hub, and extend slightly beyond the scraping elements. As shown, each of the hammers is provided with an enlarged outer surface 12 to more effectually remove the scale or rust. The hammers are pivotally mounted in recesses 13, formed in the outer surface of the hub. As shown, the inner ends of the hammers are provided with openings 14, for the reception of pivot pins 15 which are passed through these openings and received in the hub. In assembling the brush, one or more hammers are arranged in each circumferential row, and these hammers are best disposed in spiral paths, whereby only one or two hammers strike the surface being cleaned at the same time.

In the form of the invention shown in Figures 6 to 9 of the drawings, the scraping elements and hammers are each arranged in spiral paths. The construction of the scraping elements is the same as in the form of the invention heretofore described, and they extend through radial openings in a hub 16. This hub, as shown, is in the form of a sleeve or hollow cylindrical body adapted to receive the driving spindle 2. It is provided with a spiral groove 17 on its inner face, adapted to receive a fastening wire 18 which extends from one end of the hub to the other, and is passed through the openings 9 in the brush elements. The construction of the hammer support is the same as in the form of the invention heretofore described.

Referring to Figures 10 to 15 of the drawings, the method of cutting the grooves and radial openings in the hub will be described. The radial openings 5 are so small that it is impossible to cut or punch them through the material of which the hub is formed. In constructing a hub for use in the form of brush shown in Figures 1 to 5 of the drawings, the grooves 4 are cut in the interior of the two sections of the hub, one of which is shown in Figure 13 of the drawings. These grooves are cut to a predetermined depth and a plurality of longitudinal grooves 19 are then cut in the outer surface of the hub. The depth of the grooves 19 plus the depth of the grooves 4 is equal to or slightly greater than the thickness of the hub whereby the radial openings 5 are formed where the grooves intersect.

Instead of forming the interior grooves circumferentially the hub may be provided with a plurality of interior longitudinal grooves 20 as shown in Figures 10 and 11 of the drawings. The circumferential grooves are then cut on the exterior of the hub as shown in Figure 11 and the inter-

section of these two sets of grooves forms radial openings 22 similar to the openings 5. A hub constructed in this manner will form a brush substantially similar to the brush shown in Figures 1 to 5 of the drawings having the brush elements arranged in circumferential rows. The fastening wires however are arranged interiorly of the hub as shown in Fig. 16. In this form of the invention the center opening of the hub is larger and the fastening element 24 is disposed in the space interiorly of the hub, preventing outward movement of the scraping element.

In forming the spiral brush shown in Figures 6 to 9 of the drawings, the spiral grooves 17 are first formed on the interior of the hub and a plurality of longitudinal grooves 23 are then formed on the exterior. The intersections of these two sets of grooves form the radial openings 16.

Instead of using a fastening wire extending through the interior grooves of the brush a substantially U-shaped clamping element may be passed through the holes 9 in the scraping elements as shown in Figure 16 of the drawings. This element may be formed by passing a straight piece of wire through the holes 9 and then bending it to the desired form. As the scraping element substantially fills the radial openings in the hub the clamping element 24 will be disposed in the interior groove and will prevent displacement of the brush element.

The operation of the device will be apparent from the foregoing description. The brush is revolved in any suitable manner, and the scraping elements and hammers contact with the surface to be cleaned. The hammers loosen hard rust, scale and the like and the scraping elements then remove all loose material from the surface, at the same time acting as bearing members for the hammers and permit the tops of the hammers to strike the surface in an even and efficient manner.

By providing scraping elements consisting of a relatively long member 6 which is adapted to contact with the surface being cleaned, and shorter elements arranged on each side thereof, liability of breakage is reduced to a minimum. A further advantage is the provision of a scraping element consisting of straight plates projecting radially from the hub, which plates are provided with openings for the reception of a fastening wire. By rounding the outer edges of the radial openings 5, the scraping elements are made more flexible and liability of breakage due to the sharp edge that would otherwise contact with the scraping element is reduced.

It is to be understood that the forms of our invention herewith shown and described are to be taken as preferred examples of the

same, and that various changes in the shape, size, and arrangement of parts may be resorted to without departing from the spirit of the invention or the scope of the sub-
5 joined claims.

Having thus described our invention, we claim:

1. A rotary brush comprising a hub, a plurality of scraping elements projecting from said hub, each of said scraping elements comprising a substantially straight flat plate, and a plurality of similar plates arranged on each side thereof, said plates being of progressively shorter lengths, and 10 means for securing said scraping elements to said hub.
2. A rotary brush comprising a hub having a groove formed on its interior, said hub being further provided with radial open- 15

ings extending from said groove to the exterior thereof, scraping elements projecting through said openings, each of said elements comprising a substantially straight, flat plate and a plurality of shorter plates arranged on each side thereof, the inner ends 20 of said plates being provided with openings, and a fastening wire mounted in said groove and passing through the openings in said plates to retain the strips in position.

3. A brush hub provided with interior 25 and exterior intersecting grooves, the depth of the grooves being such that radial openings are formed at the points of intersection.

In testimony whereof we affix our signatures.

ALBERT C. HOLZAPFEL.
ARTHUR M. HOLZAPFEL.
